(57) **CLAIM**

The ornamental design for a vacuum cleaner with attached air filter, as shown and described.

DESCRIPTION

FIG. 1 is a perspective view showing the side, top, and rear thereof, with an attached air filter;

FIG. 2 is a side elevational view thereof; the opposite side thereof being a mirror image of the view shown in FIG. 2;

FIG. 3 is a front elevational view thereof;

FIG. 4 is a rear elevational view thereof; and,

FIG. 5 is a top plan view thereof.
